SCRAPER BUCKET

Leslie P. Green, Chicago, Ill., assignor to James Wood, Chicago, Ill.

Application May 27, 1929. Serial No. 366,335

5 Claims. (Cl. 37—147)

The invention relates to scraper buckets and has for its primary object the provision of an improved bucket of this character, so constructed and arranged as to facilitate the ready discharge of the excavated material.

Another object of the invention is the provision of an improved bucket of the character indicated, having special provisions permitting of the ready repair and replacement of the parts most liable to wear and injury in use.

Another object of the invention is the provision of a bucket of the character indicated, especially adapted for use as a drag line scraper bucket.

Other objects will appear hereinafter.

The invention consists in the combinations and arrangements of parts hereinafter described and claimed.

The invention will be best understood by reference to the accompanying drawing forming part of the specification and in which—

Fig. 1 is a perspective view of a bucket in the form of a scraper bucket and embodying the invention;

Fig. 2, an enlarged front elevation of the same with portions shown in section; and

Fig. 3, an enlarged transverse section taken substantially on the plane of the line 3—3 of Fig. 1.

The embodiment of the invention illustrated in the drawing is a drag line scraper bucket and comprises substantially vertical side walls 10 extending divergently forward from the ends of a short substantially vertical rear wall 11. Substantially vertical front walls 12 extend forwardly and substantially parallel to each other from the forward edges of the side walls 10, as shown. The rear wall 11, the side walls 10 and the front walls 12 have outwardly extending perforated securing flanges 13, 14 and 15, respectively, at their lower edges.

Associated with the rear wall 11 is a forwardly and downwardly inclined digging blade or tail member 16, and somewhat similar forwardly and inwardly inclined digging blades 17 are arranged

at the lower edges of the divergent side walls 10. The digging blades 16 and 17 are provided at their upper edges with outwardly extending perforated securing flanges 18 and 19, respectively, detachably secured respectively to the flanges 13 and 14 by means of bolts 20. Side extensions or cutter members 21 at the ends of the rear digging blade 16 overlap the rear ends of the side digging blades 17 and are secured thereto by countersunk rivets 22, as shown.

Substantially vertical lower extensions 23 are provided at the lower edges of the front walls 12, being provided at their upper edges with outwardly extending perforated securing flanges 24 detachably secured to flanges 15 by bolts 20. At their rear edges, the extensions 23 are overlapped with the forward edges of the blades 17 and secured thereto by means of countersunk bolts 25, as shown.

Draft plates 26 are secured, as shown, to the forward edges of the front walls 12—23 and serve as means for attachment of a bridle 27 for connection with the usual drag line for moving the scraper bucket forwardly in the usual way. Likewise at the rear, a clevis 28 is provided for attachment to a rear drag line 29, by means of which the bucket is moved rearwardly in normal operations.

In the embodiment of the invention illustrated, a transverse channel iron 30 is secured across the upper forward edges of the front walls 12, being secured thereto by means of vertical angle irons 31 at each side and stiffened by diagonal braces 32. The channel iron 30 also carries vertically arranged angle irons or brackets 33 to which is attached a frame work 34 which is also secured at the rear to vertical angle irons or brackets 35.

In using the scraper bucket disclosed, the same is simply dragged forward and back over the surface from which it is desired to remove material, the bucket filling by the normal digging or scraping action of the digging blades 16 and 17 and discharging its load when its motion is reversed, as is usual in scraper buckets of the character indicated. By means of the arrangement disclosed, the interior surface of the bucket is practically smooth and uninterrupted so that the excavated material may readily discharge therefrom by the action of gravity thereon.

In case of wear or injury to the digging elements, the same may be readily detached and replaced at the field of operations and without the need of special shop appliances.

The outwardly extending securing flanges form a stiffening rib around the outside of the bucket, thus greatly increasing its resistance against collapse. It is also to be noted that the said outwardly extending securing flanges furnish and provide horizontal lower surfaces of considerable extent at the tops of the digging portions of the scraper which contact with the surface of the ground when the digging means has penetrated to its full extent. When such penetration occurs, the lower surfaces of the securing

flanges constitute horizontal riding surfaces which have a tendency to prevent further penetration into the ground and thereby tend to prevent subjecting the operating apparatus to undue and heavy loads. By making the digging elements in separable parts, repairs or replacements of each part are possible without necessitating the replacement of the other digging elements. Obviously, if desired, the entire lower or digging portion of the bucket may be formed or cast in one integral piece or member, but in such case, the advantage of partial or piecemeal replacement is lost. The specific form and arrangement of parts is a simple and effective one for the purpose.

15 While I have illustrated and described the preferred form of construction for carrying my invention into effect, this is capable of variation and modification without departing from the 20 spirit of the invention. I therefore do not wish to be limited to the precise details disclosed but desire to avail myself of such variations and modifications as fall within the scope of the appended claims.

25 I claim:

1. A scraper bucket provided with a substantially vertical rear wall having an outwardly extending perforated securing flange at its lower edge; substantially vertical side walls extending forwardly and divergently from the ends of said rear wall and having outwardly extending perforated securing flanges at their lower edges; substantially vertical front walls extending forwardly and substantially parallel to each other from the forward edges of said side walls and provided at their lower edges with outwardly extending perforated securing flanges; a forwardly and downwardly inclined digging blade at the lower edge of said rear wall and provided at its upper edge with an outwardly extending perforated securing flange; inwardly inclined digging blades at the lower edges of said divergent side walls and provided at their upper edges with outwardly extending perforated securing flanges; substantially vertical extensions at the lower edges of said front walls and having outwardly extending perforated securing flanges at their upper edges; and means detachably securing said flanges together.

50 2. A scraper bucket provided with a substantially vertical rear wall having an outwardly extending perforated securing flange at its lower edge; substantially vertical side walls extending forwardly and divergently from the ends of said rear wall and having outwardly extending perforated securing flanges at their lower edges; substantially vertical front walls extending for-

70

wardly and substantially parallel to each other from the forward edges of said side walls; a forwardly and downwardly inclined digging blade at the lower edge of said rear wall and provided at its upper edge with an outwardly extending perforated securing flange; inwardly inclined digging blades at the lower edges of said divergent side walls and provided at their upper edges with outwardly extending perforated securing flanges; substantially vertical extensions at the lower edges of said front walls; and means detachably securing said flanges together. 80 85

3. A scraper bucket provided with a substantially vertical rear wall having an outwardly extending perforated securing flange at its lower edge; substantially vertical side walls extending forwardly and divergently from the ends of said rear wall and having outwardly extending perforated securing flanges at their lower edges; substantially vertical front walls extending forwardly and substantially parallel to each other from the forward edges of said side walls; a forwardly and downwardly inclined digging blade at the lower edge of said rear wall and provided at its upper edge with an outwardly extending perforated securing flange; inwardly inclined digging blades at the lower edges of said divergent side walls and provided at their upper edges with outwardly extending perforated securing flanges; substantially vertical extensions detachably secured at the lower edges of said front walls; and means detachably securing said flanges together.

4. A scraper of the class described comprising bottom side sections, a tail end member having 110 a transverse section and diverging side sections, said side sections being connected at their front ends with the rear ends of the bottom side sections, cutter members fastened to the front ends of 115 said bottom side sections and arranged in parallel relation, and top sections fastened to said bottom side sections, tail member and cutter members.

5. A scraper of the class described comprising inwardly inclined diverging bottom side sections, a tail end member having inwardly inclined transverse and diverging side sections, said side sections being connected at their front ends with the rear ends of the bottom side sections, top sections fastened to said bottom side sections and said tail member and having parallel front end portions, and cutter members fastened to the front ends of the bottom side sections and to the lower edges of said parallel front portions on the top sections. 120 125 130
